United States Patent Office

Des. 206,627
Patented Jan. 3, 1967

206,627

BOTTLE

Bruce L. Roberts, 1014 E. River Road,
Rossford, Ohio 43460

Filed Dec. 22, 1965, Ser. No. 286

Term of patent 14 years

(Cl. D58—8)

FIG. 1

The back not shown, is the same as the front, shown. The characteristic features of this design reside in the configuration shown in full lines on the drawing.

I claim:

The ornamental design for a bottle, substantially as shown and described.
